UNITED STATES PATENT OFFICE

91,288

DESIGN FOR A HANDLE

Levi E. Wheeler, Worcester, Mass., assignor to
The Washburn Company, Worcester, Mass., a
corporation of Massachusetts

Application October 31, 1932. Serial No. 45,661

Term of patent 14 years

To all whom it may concern:

Be it known that I, LEVI E. WHEELER, a citizen of the United States, residing at Worcester, in the county of Worcester and Commonwealth of Massachusetts, have invented a new, original, and ornamental Design for a Handle, suitable for kitchen and household tools or utensils, such as cake turners, can openers, egg beaters, forks, ice picks, knives, potato mashers, spoons, strainers and similar articles, of which the following is a specification, reference being had to the accompanying drawing, forming part thereof, in which:—

Fig. 1 is a perspective view of a handle showing my new design, looking at one side and end.

Fig. 2 is a similar perspective view of the handle, looking at the opposite side and end.

Fig. 3 is a central transverse cross section of the handle.

As shown in the drawing, the handle consists of a body of generally cylindrical form, the axial cross-section of the body being generally circular with projecting fins of varying width extending the length of the body.

I claim,

The ornamental design for a handle, as shown and described.

Dated this 29th day of Oct., 1932.

LEVI E. WHEELER.
